UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, LONDON, ENGLAND.

SIGHTING APPARATUS FOR ANTI-AIRCRAFT GUNS.

1,304,272.

Specification of Letters Patent.

Patented May 20, 1919.

Application filed June 21, 1917. Serial No. 176,114.

To all whom it may concern:

Be it known that we, Sir ARTHUR TREVOR DAWSON, knight, and Sir GEORGE THOMAS BUCKHAM, knight, both subjects of the 5 King of Great Britain, residing at Vickers House, Broadway, Westminster, in the county of London, England, have invented certain new and useful Improvements in or Relating to Sighting Apparatus for Anti-Aircraft Guns, of which the following is a 10 specification.

This invention relates to sighting apparatus for anti-aircraft guns in which means are provided whereby the deflection setting 15 of the sight in accordance with the speed at which the target is moving relatively to the gun, is automatically corrected for the varying angles of sight during the elevation and depression of the gun.

20 According to the invention the aforesaid correction is effected by means which are capable of adjustment in accordance with the ascertained height of the target, so that after this adjustment has been made the act 25 of elevating or depressing the gun to keep the sight on the target automatically corrects the deflection angle for the changing angle of sight and for the changing range without its being necessary to ascertain the 30 range. The said means preferably comprise a cam which is mounted on the carriage and is capable of being set angularly in accordance with the height of the target.

In order that the said invention may be 35 clearly understood and readily carried into effect, we will describe the same more fully with reference to the accompanying drawings, in which:—

Figure 1 is a side elevation showing sighting 40 apparatus provided with one form of the means for automatically varying the deflection of the sight in the vertical plane in accordance with the height of the target and the angle of sight.

45 Fig. 2 is a section taken approximately on the line 2, 2 of Fig. 1.

Fig. 3 is a view similar to Fig. 1 but showing the sighting apparatus provided with means for automatically varying the deflection 50 of the sight in both the vertical and the horizontal plane.

Fig. 3^a is a plan viewed at right angles to the sight bar B of Fig. 3 showing the

means for automatically varying the deflection of the sight in the horizontal plane. 55

Fig. 4 is a side elevation showing sighting apparatus provided with another form of the means for automatically varying the deflection of the sight in the vertical plane.

Fig. 5 is a section taken approximately on 60 the line 5, 5 of Fig. 4, and

Fig. 6 is a section taken approximately on line 6, 6 of Fig. 5.

A is part of the gun carriage and A' is the gun cradle trunnioned to the gun carriage. B is the sight bar which in the examples shown carries open sights, and B' is the sight arm pivoted to a bracket A² on the gun cradle. C is the cam which is adjustably mounted on the gun carriage and serves to 70 vary automatically the vertical deflection of the sight bar.

In the construction shown by Figs. 1 and 2, the sight bar B has a pivot b pivotally mounted in the bracket A² and the sight arm B' is pivoted upon the portion of the said pivot situated between the bracket A² and the sight bar as will be seen from Fig. 2. The cam C is pivotally mounted on the gun carriage and its angular position is adjusted 75 in accordance with the height of the target by a worm C' carried by a shaft C² which is angularly displaced by the handle appertaining to the height setting mechanism of the sighting apparatus for causing the angle 80 of tangent elevation to be automatically corrected during the elevation of the gun. Part of the cam of this height setting mechanism is indicated by the chain line E. Arranged in contact with the cam C is a roller 85 D carried by one arm of a lever D' pivoted at d to the bracket A²; the other arm of this lever engages with a stud or projection d' on a member D² slidably mounted in a longitudinal guide b' on the sight arm B'. The 90 said member D² carries near its forward end a bracket d² formed with a slot d³ which is situated transverse to the guide b' and in which is slidably disposed a block or nut D³; with this nut engages a screw d⁴ which is 95 carried by the bracket d² and is adapted to be actuated through suitable gearing by a handwheel D⁴ carried by the sliding member D². The said block or nut D³ is formed with a pin or projection d⁵ (see Fig. 2) carrying a block D⁵ disposed in a slot B²

100

105

formed longitudinally in the sight bar B. Attached to the sight bar B is a vertical deflection scale d^6 graduated in accordance with the vertical components of the relative speed of the target and attached to the block or nut D^3 is a pointer or index member d^7 situated contiguous to the said scale D^6 . The sight arm B' carries at its forward end a roller B'x bearing against the aforesaid cam E. It will be clear that rotation of the screw d^4 by the handwheel D⁴ will angularly displace the sight bar B relatively to the sight arm B' so that the slot B² then assumes an inclined position with respect to the guide b' of the sight arm B'. If the gun be then elevated, the roller D will move in contact with the cam C which has previously, as aforesaid, been adjusted in accordance with the height of the target, and in consequence the member D² will move along its guide b' carrying with it the block or nut D³. The block D⁵ will therefore move along the slot B² which as aforesaid is then at an angle to the guide b' and in consequence the vertical deflection imparted by the handwheel D⁴ will be automatically varied in accordance with the height of the target and the angle of sight. If on the other hand the gun is elevated prior to any initial adjustment for vertical deflection having been made the distance of the axis of the roller D⁵ from the axis of the pivot b will be altered during the elevation of the gun so that when the handwheel D⁴ is operated to bring the pointer d⁷ opposite the graduation on the scale d⁶ corresponding to the vertical component of the speed of the target, the angular displacement of the sight bar B relatively to the sight arm B' will vary in accordance with the position of the roller D⁵, that is to say in accordance with the height of the target and the angle of sight. So long as the pointer d⁷ lies opposite the zero mark of the scale d⁶ (which is the position shown in Fig. 1) the slot B² will be situated parallel to the guide b' and the sight bar will therefore not be displaced relatively to the sight arm when the member D² is moved along its guide b' during the elevation of the gun.

A similar arrangement to that above described for obtaining the automatic variation of the vertical deflection may also be employed for obtaining the automatic variation of the horizontal deflection. Fig. 55 shows sighting apparatus provided with such an arrangement in addition to the arrangement shown by Figs. 1 and 2 for obtaining variation of the vertical deflection. In this figure the automatic variation of the horizontal deflection is obtained by an additional cam C'' and an additional lever D'' operating to impart change of horizontal deflection to the sight bar B in 60 the same manner as described with refer- 65

ence to Figs. 1 and 2 in connection with the vertical deflection. D^{4x} is the hand-wheel appertaining to the horizontal deflection gear. In Fig. 3 the sight arm B' has a member D^2 slidably mounted thereon which carries the vertical deflection gear described with reference to Fig. 2. The block D^5 of this gear operates by means of the slot B^2 upon a bar B^{2x} which therefore receives the same motions as the bar B in Fig. 2. The sight bar B is pivoted to the rear part of the bar B^{2x} for lateral movements. The bar B^{2x} has slidably mounted thereon a member D^{2x} which is operated by the lever D^{4x} and carries the horizontal deflection gear comprising a block B^{4xx} similar to the block D^5 working in a slot B^0 in the sight bar B in a similar manner to that described with reference to the vertical deflection gear.

In the form of the invention shown by Figs. 4, 5 and 6 the sight arm B' has mounted thereon a swinging bracket B³ having a guide in which a member b³ is slidably disposed. This member has a pin b⁴ upon which is pivotally mounted a block B⁴ slidably disposed in a longitudinal slot b⁵ formed in a bar B⁵ which may constitute the sight bar itself or may have the sight bar pivoted thereto for horizontal deflection movements in which case the bar B⁵ would carry the horizontal deflection gear. The swinging bracket B³ is connected to one end of a link B⁶ the other end of which is slidably disposed in a guide B⁷ having a pivot b⁷ pivoted to the bracket A² referred to in the description of Figs. 1 and 2. Pivoted upon the said pivot between the guide B⁷ and the bracket A² are the sight arm B' and the bar B⁵. The said link B⁶ carries a roller b⁶ lying in contact with the cam C which in this case instead of being pivoted is mounted to slide in a curved guide A^x on the gun carriage. The cam C is adjusted in accordance with the height of the target by a cam F on the shaft C² referred to in the description of Fig. 1. The swinging bracket B³ has a graduated scale d⁶ and the pin b⁴ carries a pointer d⁷ as described with reference to Figs. 1 and 2. The handwheel D⁴ for imparting vertical deflection to the sight to agree with the vertical component of the relative speed of the target, is mounted on a shaft carried by the bracket B³ and connected by bevel gearing to a worm D^o gearing with teeth on the sliding member b³. By rotating the handwheel D⁴ the sliding member b³ is moved along the guide in the bracket B³, thus moving the block B⁴ at the same time along the slot b⁵ in the bar B⁵. As the guide in the bracket B³ is arranged at an angle to the slot b⁵ which is parallel to the line of sight, movement of the member b³ and the block B⁴ will angularly displace the bar B⁵ relatively to the 130

sight arm B' thereby imparting the desired vertical deflection to the sight. When the pointer d' is in its zero position the axis of the pin b⁴ will coincide with the pivotal axis of the bracket B³ and consequently elevation of the gun will merely result in the cam C rocking the bracket B³ without imparting vertical deflection to the sight. This rocking of the said bracket will vary 5 the angle between the guide in the bracket and the slot b⁵ in the bar B⁶ so that if the handwheel D⁴ is then operated the amount of vertical deflection imparted to the bar B⁵ will correspond not only to the vertical 10 component of the relative speed of the target but also to the height of the target and the angle of sight. If on the other hand the member b³ has previously been adjusted by the handwheel D⁴ as aforesaid, the axis of 15 the pin b⁴ will no longer coincide with the pivotal axis of the bracket B³, so that if the gun be then elevated the pin b⁴ will operate as a crank pin upon the bar B⁵ during the 20 rocking of the bracket B³ and the vertical deflection will be automatically varied for 25 the height of the target and the angle of sight.

A similar arrangement to that described with reference to Fig. 4 can, as is the case 30 with the arrangement shown by Figs. 1 and 2, be employed for automatically varying the horizontal deflection of the sight.

What we claim and desire to secure by Letters Patent of the United States is:—

35 1. In sighting apparatus for anti-aircraft guns, the combination of means operating on the sight to set it for deflection to agree with the speed of the target relatively to the gun, and means, capable of adjustment 40 in accordance with the ascertained height of the target also operating on the sight to automatically correct the said deflection setting of the sight for the changing angle of sight and for the changing range during the 45 elevation and depression of the gun, without its being necessary to ascertain the range, and supporting means for said elements.

2. In sighting apparatus for anti-aircraft guns, the combination of means operating on 50 the sight to set it for horizontal deflection to agree with the speed of the target relatively to the gun, and means, capable of adjustment in accordance with the ascertained height of the target also operating 55 on the sight to automatically correct the said horizontal deflection setting of the sight for the changing angle of sight and for the changing range during the elevation and depression of the gun, without its being necessary to ascertain the range, and supporting means for said elements.

3. In sighting apparatus for anti-aircraft guns, the combination of means operating on the sight to set it for vertical deflection 60 to agree with the speed of the target rela-

tively to the gun, and means, capable of adjustment in accordance with the ascertained height of the target also operating on the sight to automatically correct the said vertical deflection setting of the sight for the 70 changing angle of sight and for the changing range during the elevation and depression of the gun, without its being necessary to ascertain the range, and supporting means for said elements. 75

4. In sighting apparatus for anti-aircraft guns, the combination of means operating on the sight to set it for both horizontal and vertical deflection to agree with the speed of the target relatively to the gun, and means, capable of adjustment in accordance with the ascertained height of the target also operating on the sight to automatically correct the said deflection settings of the sight for the changing angle of sight and 80 for the changing range during the elevation and depression of the gun, without its being necessary to ascertain the range, and supporting means for said elements. 85

5. In sighting apparatus for anti-aircraft guns, the combination with the sight arm and the sight, of a device interposed between said arm and sight for manually setting the sight for horizontal deflection to agree with the speed of the target relatively to the gun, 90 a cam device capable of adjustment in accordance with the ascertained height of the target, and means, operated upon by said cam device, for automatically correcting the said horizontal deflection setting for the changing angle of sight and the changing range during the elevation and depression of the gun, without its being necessary to ascertain the range, and supporting means for said elements. 95

100 6. In sighting apparatus for anti-aircraft guns, the combination with the sight arm and the sight, of a device interposed between said arm and sight for manually setting the sight for vertical deflection to agree with the speed of the target relatively to the gun, 105 a cam device capable of adjustment in accordance with the ascertained height of the target, and means, operated upon by said cam device for automatically correcting the said vertical deflection setting for the changing angle of sight and the changing range during the elevation and depression of the gun, without its being necessary to ascertain the range, and supporting means for said elements. 110

115 7. In sighting apparatus for anti-aircraft guns, the combination with the sight arm, and the sight bar, of a member mounted to slide longitudinally upon said sight arm, 120 means capable of adjustment in accordance with the ascertained height of the target for sliding said member during the elevation and depression of the gun, a bracket carried by said member, a second member mounted 125

130

- 4
- to slide on said bracket in a direction transverse to the direction of sliding movement of the first mentioned member and engaging with a guide in the sight bar, this guide being normally situated parallel to the direction of sliding movement of the first mentioned member, and means for sliding the second member in accordance with the speed of the target relatively to the gun, and supporting means for said elements.
  - 5 8. In sighting apparatus for anti-aircraft guns, the combination with the sight arm, sight bar and the member carrying the sight bar, of a swinging bracket carried by said sight arm, a member slidably mounted on said bracket and coöoperating with a
  - 10
  - 15

guide formed on a member carrying the sight bar, means for moving the first mentioned member in accordance with the speed of the target relatively to the gun, and 20 means, capable of adjustment in accordance with the ascertained height of the target, for rocking said bracket automatically during the elevation and depression of the gun, and supporting means for said elements. ✓

25

In testimony whereof we have hereunto affixed our signatures.
